UNITED STATES PATENT OFFICE.

CHARLES W. MUNZ, OF DETROIT, MICHIGAN.

ROUND-TOP EXTENSION-TABLE.

1,019,826.

Specification of Letters Patent. Patented Mar. 12, 1912.

Application filed April 2, 1906. Serial No. 309,535.

To all whom it may concern:

Be it known that I, CHARLES W. MUNZ, a citizen of the United States of America, residing at Detroit, in the county of Wayne 5 and State of Michigan, have invented certain new and useful Improvements in Round-Top Extension-Tables, of which the following is a specification, reference being had therein to the accompanying drawings.

10 The invention consists in the means employed for storing detachable leaves beneath the stationary table top; and further in the peculiar construction, arrangement and combination of parts as hereinafter set forth.

15 In the drawings, Figure 1 is a bottom plan view of the extended table, showing in dotted lines the leaves in stored position; Fig. 2 is a sectional side elevation; Fig. 3 is a perspective view of the adjoining ends of 20 a pair of leaves; and Fig. 4 is a perspective view of the connection between the pedestal and the stationary table top.

A is the stationary top of a round top table, B the supporting pedestal, and C the 25 segmental leaves by which the table top is extended. These leaves preferably are provided with a tongue and groove engagement with the peripheral edge of the stationary table top, as illustrated at a, and are also 30 preferably provided with a groove b at one end of each segment, and a corresponding tongue c at the opposite end.

D is a depending rail extending about the stationary table top near the edge thereof.

35 It is one of the objects of the invention to provide means for storing the leaves beneath the stationary top and within the space enclosed by the depending rail D. It is a further object to accomplish this without 40 cutting away any portion of the rail D. To this end, I have provided one or more leaf-holding racks, which are capable of being lowered to receive the leaves and then raised to a position where they will be concealed 45 from view by the stationary depending rail D. As shown, two leaf-storing racks E E' are arranged upon opposite sides of the pedestal B. This pedestal is preferably secured to the under side of the stationary

50 top through the medium of a central cross-bar or bolster F, which is mortised into the upper end of the pedestal and is secured thereto as by the central bolt G. The cross-bar or bolster F also forms a means of attaching the racks, which preferably consist 55 of a pair of arms d d', cross-connected at

their outer ends by the bars e, preferably of segmental form and pivotally connected at their inner ends to the depending brackets f on the bolster F. The arms d d' for the 50 opposite racks E may be arranged with their inner ends adjacent to each other and both secured by a single pivot bolt g to the bracket f.

H is a latch-dog for engaging with the 65 outer end of each of the racks E and holding the same in raised position.

The racks constructed as just described when disengaged from the dogs H are capable of dropping into an inclined position, 70 indicated in dotted lines in Fig. 2. In this position, they are sufficiently below the lower edge of the rail D to permit of inserting the separate leaves C and resting them upon the arms E E', as indicated in dotted lines 75 in Fig. 1. The length of the leaves is limited so that they will fit within the space inclosed by the rail D, and the depth of the space between the racks and the stationary top is sufficient to receive a pile of at least 80 one-half the number of leaves required to surround the stationary top. Thus, all of the leaves may be stored in the two racks and, when the latter are raised into engagement with the latch-dogs H, they will be 85 completely concealed from view.

For securing the leaves to the stationary top, I preferably provide each with an inwardly-extending arm I, adapted to engage with the slot in the top of the rail D and to 90 extend inward beneath the stationary top of the table. A set-screw J is also preferably provided for clamping these inwardly-extending arms, thereby locking them from movement in any direction and, by reason of 95 the tongue and groove engagement between the leaves and the edge of the stationary top and between adjoining ends of the leaves, the extension sections are held rigidly in position. This set screw engages a bearing for 100 the slide secured adjacent to the rail D. As shown, the arms I are preferably arranged at one side of the center of the leaves, so as to avoid interference with the pedestal in 105 stored position.

With the construction described, the table is provided with self-contained means for extending the same, and the operation of extending or of contracting the table is 110 quickly and easily performed.

What I claim as my invention is,—
The combination with a round stationary

table top, of a series of leaves for surrounding the same and extending the diameter thereof, a central pedestal for supporting said stationary top, a cross-bar or bolster for bracing said top upon said pedestal, racks pivotally secured to said bolster at their inner ends and extending oppositely therefrom beneath said stationary top, said racks being adapted to receive all of said leaves,

and means for locking the outer ends of said racks to the stationary top.

In testimony whereof I affix my signature in presence of two witnesses.

CHARLES W. MUNZ.
